CLAIM

The ornamental design for a ladder platform with stairs, as shown and described.

DESCRIPTION

FIG. 1 is a top, front, right, perspective view of a ladder platform with stairs, illustrating a first embodiment of the design;

FIG. 2 is a top, rear, right, perspective view corresponding with FIG. 1;

FIG. 3 is a front elevation view corresponding with FIG. 1;

FIG. 4 is a rear elevation view corresponding with FIG. 1;

FIG. 5 is a left side elevation view corresponding with FIG. 1;

FIG. 6 is a right side elevation view corresponding with FIG. 1;

FIG. 7 is a top plan view corresponding with FIG. 1;

FIG. 8 is a bottom plan view corresponding with FIG. 1;

FIG. 9 is a top, front, right, perspective view of a ladder platform with stairs, illustrating a second embodiment of the design;

FIG. 10 is a top, rear, right, perspective view corresponding with FIG. 9;

FIG. 11 is a front elevation view corresponding with FIG. 9;

FIG. 12 is a rear elevation view corresponding with FIG. 9;

FIG. 13 is a left side elevation view corresponding with FIG. 9;

FIG. 14 is a right side elevation view corresponding with FIG. 9;

FIG. 15 is a top plan view corresponding with FIG. 9; and,

FIG. 16 is a bottom plan view corresponding with FIG. 9. The broken lines represent portions of the ladder platform with stairs that form no part of the design.
